Primary Examiner — Zenia Bennett*Assistant Examiner* — Rashida C McCoy(74) *Attorney, Agent, or Firm* — Cowan, Liebowitz & Latman, P.C.; Mark Montague; Serge Krimnus(57) **CLAIM**

The ornamental design for shoe, as shown and described.

DESCRIPTION

FIG. 1 is a perspective view showing the shoe of the present invention;

FIG. 2 is a top plan view thereof;

FIG. 3 is a bottom plan view thereof;

FIG. 4 is a right elevational right view thereof;

FIG. 5 is a left elevational view thereof;

FIG. 6 is a front elevational view thereof; and,

FIG. 7 is a rear elevational view thereof.

Broken lines showing portions of the shoe are for illustrative purposes and form no part of the claimed design.
